(57) **CLAIM**

An ornamental design for a warning light with speaker, as shown and described.

DESCRIPTION

FIG. 1 is a front side view of the design according to the invention.

FIG. 2 is a back side view of the design according to the invention.

FIG. 3 is a top view of the design according to the invention.

FIG. 4 is a bottom view of the design according to the invention.

FIG. 5 is a left side view of the design according to the invention.

FIG. 6 is a right side view of the design according to the invention.

FIG. 7 is a top perspective view of the design according to the invention; and,

FIG. 8 is a bottom perspective view of the design according to the invention.

The elements shown in broken lines are for illustrative purposes only and form no part of the claimed design.
